(57) **CLAIM**

The ornamental design for a charging stand for body cleansing apparatus, as shown and described.

DESCRIPTION

FIG. 1 is a front, right side perspective view of a charging stand for body cleansing apparatus showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, right side, perspective view of the charging stand for body cleansing apparatus shown with environmental structure. The broken line showing in FIG. 8 is for the purpose of illustrating environmental structure and forms no part of the claimed design.

The broken lines indicate portions of the article that form no part of the claimed design.
